Primary Examiner — Catherine A Tuttle(74) Attorney, Agent, or Firm — Minder Law Group;
Willy H. Wong(57) CLAIM

The ornamental design for a dispenser bottle, as shown and described.

DESCRIPTION

FIG. 1 is a front view of a dispenser bottle showing my new design.

FIG. 2 is a back view thereof.

FIG. 3 is a left view thereof.

FIG. 4 is a right view thereof.

FIG. 5 is a top view thereof; and,

FIG. 6 is a bottom view thereof.

The broken lines show portions of the dispenser bottle that form no part of the claimed design.
